APPARATUS FOR PLAY AND SPORT

Rudolf Heimers, Churubusco, D. F., Mexico

Application April 28, 1931, Serial No. 533,521
In Mexico April 29, 1930

8 Claims. (Cl. 272—1)

The invention relates to apparatus for play and sport in their broadest sense, in which apparatus a carrier is united with a rope winding and unwinding itself on a flywheel rotated by direct or indirect means, so that when the flywheel is rotated in one way or another, changes are effected by means of said rope in the location of said carrier together with its load.

In a narrow sense, the object of the present invention is to create new devices for the amusement of people on pleasure grounds, which by closely connecting sport and sensation answer modern demands, while in its broad sense the object of the invention is to provide means for new kinds of sports.

The principle underlying the present invention consists in the function of a wheel or flywheel, on the axle of which a rope winds and unwinds itself, which rope by alternate pulling and loosening first produces increasing oscillations of the wheel and finally brings it into full rotations, whereby the rope is alternatively wound and unwound. The automatic winding and unwinding of said rope produces a progressively increasing displacement of the load suspended from it, without it being necessary to increase the periodically repeated force applied for rotating the wheel. The importance of the present apparatus for play resides in the more or less vertical rocking movements of the carrier, while its application for sport calls for an active participation of the player in producing and in maintaining the performance of the apparatus. In the latter case the person operating the apparatus is preferably mounted on the carrier or suspended from the rope, which obviously can by itself constitute the carrier or serve as such.

Many different forms of construction are possible with apparatus based upon the aforesaid principle, and several of these forms are illustrated in the accompanying drawings.

Figure 1 is a front view, partly in section, of an apparatus with the flywheel at its top.

Figure 2 is a side view of the apparatus shown in Figure 1.

Figure 3 shows the weighted flywheel with the rope attached, in the position before it is made to oscillate.

Figure 4 is a lateral view of a similar apparatus with the flywheel at the bottom.

Figure 5 is a front view of the apparatus shown in Figure 4.

Figure 6 represents an apparatus with the flywheel at the bottom and the carrier balanced by counterweights.

Figure 7 is a cross section on line a—b of Figure 6.

Figure 8 shows one of the dented levers for starting the displacement of the carrier in the apparatus shown in Figure 6.

Figure 9 is a front view of an apparatus similar to the one shown in Figures 4 and 5, but placed on a moving platform.

Figure 10 is a partial side view of the apparatus shown in Figure 9.

Figure 11 represents an apparatus in which the carrier is formed by a winged horse.

Figure 12 shows the horse of Figure 11 opened, for demonstrating its inside mechanism.

Figure 13 is a cross section through the neck of the horse, showing the mechanism for changing the winding of the rope from one to the other of the circular grooves of an auxiliary flywheel.

The apparatus illustrated in Figures 1 and 2 comprises a square tower 1, reinforced by cross members for greater stability. The top of this tower carries the horizontal axle 2 of a heavy flywheel 3 having a deep circular groove in which the rope 4 winds and unwinds itself. Said rope is fastened with one extremity to the bottom of said groove, and the flywheel 3 is weighted at a point 5 of its rim. From the other extremity of the rope 4 is suspended a horizontal beam 6, from which hangs by two short ropes or bars 7 a horizontal bar 8. By using bars instead of ropes 7, greater safety is obtained and torsional motions of bar 8 are prevented. The beam 6 is further connected with the flywheel 3 by two ropes 9 fastened to said beam at points located at equal distances from the center rope 4 and which wind and unwind themselves in circular grooves 10 provided on the sides of the flywheel 3. These ropes 9 also serve for preventing undesirable torsions and at the same time as safety means against accidents caused by the rupture of the rope 4. For impeding excessive swinging of the ropes 4 and 9, they are made to pass between a pair of rollers 11 placed transversely to and below the flywheel 3.

The apparatus described being in repose, the weight of the ropes 4 and 9, the beam 6 and the bars 7 and 8 stretch the center rope 4 so that it hangs down from the deepest point of the central groove of the flywheel, in which position the weight 5 is raised up on one side of said wheel. When the person using the apparatus lifts the bar 8, with its bars and ropes connecting it to the beam 6, the weight suspended from the flywheel is diminished, and the weight 5 swings down in the direction of the arrow in Figure 3, partially winding up the rope 4. The bar 8 is then pulled down, raising again the weight 5, and this movement is repeated several times in quick succession, producing an increasing oscillation of the flywheel, until it starts to rotate completely. By reason of its weight and of the centrifugal force developed, the rope 4 on winding itself will lift the player from the ground, and on unwinding will let him down, and this movement will continue as long as the flywheel can be kept

in full alternate rotations by means of lifting movements produced in determined moments by the arms or legs of the player, depending on whether he is hanging from the bar 8 or standing on it. For preventing shocks when reaching its highest position, the beam 6 is provided at its ends with elastic shock absorbers 12 striking against stops 13 secured to the sides of the tower 1.

The apparatus shown in Figures 4 and 5 comprises two vertical supports 14, each formed by two spaced beams suitably braced to the ground. The bar 8 passes with its ends between the two beams of each support, and the horizontal beam 6 also has two extensions 6^a which pass between said supports, said bar and beam being connected by two vertical bars 7, providing stability and absence of torsional motions between the laterally guided bars 6^a and 8. The center of the beam 6 is attached to the rope 4, which passes over a grooved pulley 15 and from there downward to the groove of the flywheel 3 placed on or below the ground. In this apparatus, a counterweight 16 is secured to the down-hanging portion of rope 4, which counterweight, when the rope has been wound up and the beam 6 approaches its highest position, strikes against a pivoted lever 17 acting as a brake against the wheel 3. Said wheel, in its dead position, is weighted at the bottom and the rope 6 encircles half of the bottom of its groove, as shown in Figure 4, the steps for oscillating and rotating it being substantially the same as described with reference to Figure 1, with the difference that the oscillation of the wheel 3 is started by pulling down the bar 8 instead of lifting it as in Figure 1. The shock absorbing devices in the apparatus just described comprise a curved spring 18 against which strikes the beam 6 on reaching its highest position, and a spring suspension 19 between said beam 6 and the rope 4. Spiral springs 19^a are further provided in the lower part of the space between each support 14, for receiving the thrust of the descending bar 8, said springs serving at the same time as safety devices against rupture of the rope 4. The bar 8 may also be detained in a fixed position by bolts 20 passing through it and the supports 14, and may then be used as an ordinary horizontal bar for gymnastical exercises. Such exercises may also be practiced while the bar 8 rises and descends through the revolutions of the flywheel.

Figures 9 and 10 show the same apparatus described with reference to Figures 4 and 5, but mounted on a platform 21 moving on wheels 22. The downward movements of the bar 8 are therefore made use of for moving forward the front pair of said wheels 22, by means of racks 23 extending vertically down from said bar and suitably guided in the space between the beams of each support 14. These racks engage pinions 24 mounted on a shaft 25, said pinions being connected by suitable means, such as chains 26, with pinions 27 placed on the axle 28 of the front wheels. A ratchet wheel 29 on the same axle 28, combined with a fixed pawl 30, permits the wheels 22 to be only turned in a forward direction, being disengaged when the racks 23 ascend.

In Figure 6 is shown an apparatus in which the carrier takes the form of a cage 31 in which two persons may sit, one opposite to the other. The rope 4 is attached to bars 32 placed transversely at the top and at the bottom of said cage and passing between two vertical supports 33 formed of channel irons, with a continuous rack 34 inside of each channel, said supports being

suitably braced and spaced at the top and at the bottom by metal plates 35. The lower part of the rope 4 extends from the inferior bar 32 to the flywheel, and the other part of said rope, being fastened to the upper bar 32 by a spring suspension 19 as in Figures 4 and 5, passes over a grooved pulley 15 at the top of the column 33 and is secured to a counterweight 35 sliding on a steeply inclined surface 36. This counterweight 35 is connected by a loose rope or chain 35^a with another weight 37, which in turn is similarly connected with a third weight 38, both weights 37 and 38 resting on fixed seats 39. The gradual taking up and raising of the auxiliary weights 37 and 38 acts as a brake when the cage 31 is descending, this braking effect being entirely automatic. The counterweight 35 may also be substituted by another carrier containing one or more persons, and which is raised as the other carrier descends.

For starting the rocking movement of cage 31, necessary for initiating the preliminary oscillations of the flywheel, as described, each person sitting in said cage manipulates a lever 40 having attached a dented segment 41, which engages the corresponding rack 34, the cage being lowered by pulling said levers backward, and raised by pushing them forward. The same levers 40 also serve as brakes to be used by any of the players for detaining the cage at any desired height. The apparatus described differs from the preceding apparatus especially in that the starting point for its operation is located above the carrier.

Figure 11 represents an apparatus in which the carrier is formed by the figure of a horse 42 moving up and down a column 33 constructed in a manner similar to the one described with reference to Figure 6, of two channel irons 33 with a rack 34 in each channel, and spaced by other channel irons 44 so as to leave a hollow center.

The horse 42 is preferably made entirely hollow and in a reared position, the column 33 passing through its entire length. Two pairs of grooved wheels 45 bearing against the outward edges of the channel irons 33 and fastened with their cross members 46 to the inside of the horse, serve as guides for keeping it in an upright position and for reducing friction. The saddle 47 of the horse is preferably made of curved spring steel resting on a similarly curved spring 48, in order to make it resilient and shock absorbing.

The up and down movements of the horse along the column 33 starting the oscillations of the flywheel, are carried out by means of dented segments 49 and 50, pivoted at their apex and held out of engagement with the racks 34 by springs 51, which pull the segment 49 up and the segment 50 down. The first segment 49 is attached by a cross member to the stirrups 52, which on being pushed down, make said segment 49 engage the corresponding rack 34, giving an upward movement to the horse. The second segment 50 is attached to the reins 53 which are led over rolls 54 and 55 at the throat and the mouth of the horse, and moves up by a pull on the reins, giving a downward movement to the horse.

The rope 4, after passing from the flywheel 56 up the inside of the column 33 and over a grooved pulley 57 at the top of the tower 58 sustaining said column, is attached with its other extremity to a roller 59 on which the rope winds and unwinds itself. The axle 60 of this roller passes on both sides through a downwardly and

backwardly inclined slot 61 and is provided with a pinion 62. The axle 60 is further secured to the ends of a second rein 63. By pulling on this rein, the axles 60 glides back and down in the slots 61, thereby bringing the pinion 62 in engagement with the corresponding rack 34 and winding up the rope 4 on the roller 59 as the horse moves down. To the pinion 62 is secured a ratchet wheel 64, detained by a pawl 65, to which pawl are fastened by a transverse member 10 the ends of long flat springs 66, located on the outside of both sides of the horse, so as to be easily reached by the knees or heels of the rider. By pressing or pushing inward with the legs these 15 flexible springs, their length is reduced and the pawl 65 is disengaged from the teeth of the ratchet wheel 64, and by loosening simultaneously the reins 63, letting the axle 60 slide up in its bearings and disengaging it from the rack, the rope 20 4 unwinds itself from the roller 59 and the horse falls.

When using a relatively high column on which the horse slides up and down, it may be advisable to reduce at a certain height the velocity with 25 which the rope winds itself upon the axle of the wheel 56, or to give to the rider a new starting point, to be determined before-hand. For this purpose said wheel 56 is provided with two grooves, to one of which the rope is fastened. 30 As soon as this groove is filled with the turns of the rope, at a certain height attained by the horse, a transverse bolt 67 (Figures 12 and 13) lying in two vertical slots 68 of the column 33 (bolt head and slot being shown proportionally 35 too large in Figure 12 for greater clearness) is caught by two inwardly protruding hinged claws 69 secured to the neck inside of the horse, and after being lifted in said slots, is pushed sideways into an enlarged opening 68^a at the top 40 and on one side of said slots. The bolt 67 is attached to a rope 70, which on being raised together with said bolt, actuates a lever 71 located at the foot of the column 33, which lever pulls the rope 4 towards the second groove in the wheel 45 56, in which it continues winding itself up. The diameter of this second groove being smaller than the diameter of the first groove filled with the rope, the velocity of ascension of the horse is reduced. Several such devices may be provided 50 at different heights of the column so as to reduce periodically the ascending speed, or for limiting the up and down movements of the horse to certain predetermined stories or portions of the column. For disengaging the bar or 55 bars 67 from the openings 68^a, a sliding lever 72 is pushed against the conical extremities of said bar 67, dislodging it from said openings and letting it fall down in the slots 68, whereby the rope 4 returns to its former position above the first 60 groove in wheel 56. If it is desired that the bolt lifting device should not actuate, the hinged front part of the claws 69 is raised by pulling on the ring 69^a and securing this ring in a hook 69^b.

For obtaining a higher number of revolutions 65 and thereby a greater centrifugal force, the wheel 56 is geared to a big flywheel 73, which is provided with a pinion or pulley 74 for transmitting its rotation to a speed regulator or any other mechanism. The flywheel 73 is further provided 70 with a crank lever 75 for imparting by hand the first oscillations or rotations, if this should be desired.

The horse may further carry lateral wings 76 pivoted on a transverse member 77 passing through the horse. Said member is provided with a pin 78 which is periodically engaged by a number of transverse pins 79 extending from the 5 face of the pinion 62, producing a flapping of said wings as said pinion revolves.

A shock absorber 80, formed by a strong spiral spring, serves as an aid for braking the fall of 10 the horse as it finishes its descent.

Having now particularly described and ascertained the nature of my said invention and in what manner the same is to be performed, I declare that what I claim is:—

1. Apparatus of the class described, comprising 15 a vertically movable carrier element, a flywheel, mounted at a point above the carrier, for rotation in reverse directions and having an eccentrically arranged weight, a cord connected to the flywheel to be wound and unwound thereon 20 and also connected to the carrier element so that the latter is suspended from the flywheel and arranged for reciprocating vertical movement to impart reverse initial rotations to the flywheel, and to be lifted by the winding up of the cord 25 incident to the momentum of the rotating flywheel.

2. Apparatus as claimed in claim 1, including 30 a second cord connected to the flywheel to be wound and unwound thereon and also connected to the carrier element.

3. Apparatus as claimed in claim 1, in which the carrier element is a bar.

4. Apparatus as claimed in claim 1, including 35 means to absorb shocks incident to change of direction of movement of the carrier at the ends of the path of movement thereof.

5. Apparatus for play and sport, comprising a flywheel mounted at an elevated point for rotation in reverse directions, a carrier element below the flywheel, winding means connected to the flywheel to be wound and unwound thereon, and also connected to the carrier element, the latter being arranged for vertical reciprocating movement to impart reverse initial rotations to 45 the flywheel, and to be pulled by the winding up of the winding means incident to momentum of the rotating flywheel.

6. Apparatus of the class described, comprising 50 a carrier element arranged for reciprocating movement, a flywheel mounted for rotation in reverse directions and spaced from the carrier, and having an eccentrically arranged weight, a cord having one end connected to the flywheel, said cord being also connected to the carrier element so that when the carrier element is initially moved in one direction against the resistance of the flywheel and then released the flywheel will be caused to rotate and the pull exerted by such movement of the carrier element will cause the 55 cord to be unwound on the flywheel and the momentum of the flywheel will cause the cord to be rewound thereon and thereby move the carrier element in the reverse direction.

7. Apparatus as claimed in claim 6, including 60 a brake for the flywheel and means to actuate the brake.

8. Apparatus as claimed in claim 6, including 70 a guide element for the carrier.

RUDOLF HEIMERS.
